UNITED STATES PATENT OFFICE

WILLIAM R. RENNINGER, OF DIAMOND, OHIO

CYLINDER GOLD SEPARATOR

Application filed July 24, 1931. Serial No. 552,990.

The present invention relates to a gold separator and has for its prime object to separate gold from sand, gravel and the like in an expeditious and efficient manner and to handle the gold bearing sands, gravel and the like in large quantities and with great rapidity so as to make procurable gold dust that is usually lost.

Another very important object of the invention resides in the provision of a gold separator of this nature which is comparatively simple in its construction, strong and durable, thoroughly reliable in operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of a machine embodying the features of my invention.

Figure 2 is an end elevation thereof.

Figure 3 is a vertical longitudinal section therethrough.

Figure 4 is a vertical transverse section taken substantially on the line 4—4 of Figure 1.

Figure 5 is a vertical transverse section taken substantially on the line 5—5 of Figure 1.

Figure 6 is a detail section taken substantially on the line 6—6 of Figure 5.

Figure 7 is a detail section through one end of the cylinder and screen.

Figure 8 is an end elevation of the cylinder.

Figure 9 is a side elevation of the screen, and

Figure 10 is a sectional view through the nozzle.

Referring to the drawings in detail, it will be seen that numerals 5 denote a pair of transverse base members connected together by longitudinal members 6. A framework rises from the base members and includes two pair of standards 7, one pair rising from each base member 5. A cross bar 8

connects the upper ends of each pair of standards. Longitudinal bars 9 extend between the cross bars 8. Cross bars 10 extend between lower portions of the standards adjacent longitudinal bars 11. A pair of spaced parallel hexagonal frames 12 and 14 are mounted in the frame work, the former being slightly higher than the latter. Brackets 15 project inwardly from the frames 12 and 14 and have journalled therein rollers 16 to ride in annular channelled tracks 17 about a cylinder 18. A head 19 is mounted in the front end of the cylinder and is formed with a central circular opening 20. A plurality of lugs 21 project inwardly from the head 19 circumjacent the opening 20. A cylindrical screen 22 is provided with a ring 23 at one end to be received between the lugs 21 and at the other end is provided with a ring 24 with a plurality of arms 25 thereon having friction shoes 26 of rubber or the like on the ends thereof for frictionally engaging the interior wall at the lower end of the cylinder. An annular channelled band 27 is disposed about the central portion of the cylinder 18 and has trained therein a belt 28 also trained over a pulley 29 on a shaft 30. This shaft 30 is operatively connected with a prime mover such as an engine 31 and also with a water pump 32, the engine and water pump being mounted on a platform 33. The cylinder 18 is made of copper, triple plated with silver on the inside thereof.

A hopper 36 is supported by a bracket structure 37 from the frame 12 and extends through the opening 20 and the bottom thereof inclines downwardly and inwardly. A spray nozzle 40 is mounted above the hopper 36 on the frame work and has leading thereto a conduit 41 with the valve 42 therein. A conduit 43 is coupled with the conduit 41 and also with a conduit 44 which is coupled with a perforated pipe 45 leading longitudinally through the upper portion of the cylindrical screen 22 and supported by a bracket 46 at its rear end which is closed as at 47. The bracket 46 is movable so as to be moved out of the way when inserting the screen into the cylinder or removing the same therefrom. The conduit 43 leads from the water pump 32.

In using the machine the cylindrical screen is withdrawn from the cylinder and quicksilver is applied to the silver plated interior of the cylinder. The screen is then replaced

5 in the cylinder. The engine is then started causing the rotation of the cylinder with the screen therein. The water is forced through the conduit 43 into the nozzle 40 and the spray pipe 45. The water runs out of the rear end of the cylinder. The gold bearing sand and gravel are thrown in the hopper and washed through the screen which removes stones and the like which are too large to pass there-through.

10 15 The residue passes through the screen on to the inside face of the cylinder as it revolves and the gold adheres to the quicksilver while the sand and gravel wash out at the rear end of the cylinder. The screen is removed and the cylinder is wiped out with a piece of soft rubber and the gold extracted from the quicksilver.

20 25 It is thought that the construction, operation, utility and advantages of this invention will now be quite apparent to those skilled in this art without a more detailed description thereof.

30 The present embodiment of the invention has been described in considerable detail merely for the purposes of exemplification since in actual practice it attains the features

of advantage enumerated as desirable in the statement of the invention and the above description.

Having thus described my invention, what I claim as new is:

A device of the class described comprising a supporting frame, a diagonally arranged cylinder rotatably supported therein and having its lower end open, a head having a centrally arranged opening therein closing the other end of the cylinder, lugs on the interior face of said head, adjacent the opening, a screen having a ring at one end portion resting on the lugs, said screen being of cylindrical shape and located in the cylinder, outwardly extending projections on the other end of the screen, friction material on the outer ends of the projections for frictionally engaging the internal wall of the cylinder at the lower end thereof, means for rotating the cylinder, a hopper extending into the opening in the head of the cylinder, means for spraying liquid into the hopper, a spray pipe passing through the cylinder and the screen, means for connecting the upper end of said pipe to a liquid supply, and a bracket connected with the lower end of the pipe and removably connected with a part of the frame.
